UNITED STATES PATENT OFFICE.

GEORGE HARLAND BOWDEN, OF WESTMINSTER, LONDON, ENGLAND.

SETTING OF STEAM BOILERS.

Application filed June 26, 1922. Serial No. 570,786.

To all whom it may concern:

Be it known that I, GEORGE HARLAND BOWDEN, a British subject, residing at Westminster, London, England, have invented 5 certain new and useful Improvements in the Setting of Steam Boilers, of which the following is a specification.

This invention relates to the setting of steam boilers of Lancashire or Cornish or 10 other cylindrical type with internal flues within the shell of the boiler and side and bottom flues exterior to the shell of the boiler.

In this construction of boiler plates are 15 affixed to project longitudinally from the rear of the boiler, and laterally or radially at each side near the front such plates fitting into grooves in the brick work or masonry to prevent the escape of the heated gases 20 direct into the chimney flue at the back of the boiler and the inlet of cold air to the front and the sides of the boiler and also allow for any movement of the boiler shell due to expansion and contraction.

25 According to the invention I bond the brickwork both at the front and back of the boiler by a steel reinforcement with longitudinal and transverse members interlocked which is placed between the courses 30 of bricks, the longitudinal members extending nearly the full length of the fender or partition walls and the transverse members extending across the walls from side to side and through holes or slots in the plates projecting from the boiler shell.

35 The invention will be fully described with reference to the accompanying drawings.

Fig. 1 is an elevation of front end of boiler partly in section through one side flue.

40 Fig. 2 is a plan of front end of boiler with section through the side flues on line 2—2, Fig. 1.

Fig. 3 is an elevation of rear end of boiler 45 partly broken away and transverse section through the back flues on line 3—3, Fig. 4.

Fig. 4 is a plan of rear end of boiler with section through the fender walls and flues on line 4—4, Fig. 3.

50 Fig. 5 is a sectional elevation enlarged of the back plate and fender wall D on line 5—5, Fig. 6.

Fig. 6 is a sectional plan enlarged of back plates and fender wall.

The boiler A is of any ordinary cylindrical type with the plates B affixed at the back by the angle irons b and the plates C affixed at the front by the angle irons c, the plates being provided with slots b' and the plates C with slots c'. 55

The flues at the rear of the boiler are built with fender or partition walls D and at the front with the walls E, the walls D being formed with grooves d into which the back plates B are fitted and the walls E with grooves e into which the front plates C are 60 fitted. F are dampers by which the side flues G may be cut off from the chimney flue G' to regulate the draught to the chimney (not shown).

70 Into the fender or partition walls D and E reinforcements H with longitudinal members h and transverse members h' are built in between the courses of the bricks to bond the bricks together and strengthen the 75 walls. The longitudinal members h are disposed at the sides of and extend some distance behind the grooves d and e in the walls and the transverse members h' are connected to and retain the longitudinal members h in 80 position one of the transverse members h' of each passing through the slots b' and c' in the plates B and C. At the back of the boiler above the projecting plates B a transverse channel iron K is affixed to the boiler 85 and an angle iron M is carried by the brick work one flange of which depends into the interior of the channel leaving free play between them to permit of expansion and contraction of the boiler in any direction. 90

The grooves d and e and the channel K may be packed with asbestos in powder or other form.

95 What I claim as my invention and desire to protect by Letters Patent is:—

In an expansion joint for a steam boiler the combination with a plate affixed to the boiler of supporting brickwork a groove formed therein, longitudinal reinforcing members disposed at either side of the 100 groove, transverse reinforcing members disposed behind the groove and transverse reinforcing members passing through the groove and through apertures in the plate.

105 In testimony whereof I have hereunto set my hand.

GEO. HARLAND BOWDEN.
